UNITED STATES PATENT OFFICE.

JOHN McMULLEN, OF BUFFALO, NEW YORK.

JOURNAL-BOX-PACKING RETAINER.

1,303,933.

Specification of Letters Patent. Patented May 20, 1919.

Application filed July 5, 1917. Serial No. 178,662.

To all whom it may concern:

Be it known that I, JOHN McMULLEN, a citizen of the United States, residing at Buffalo, in the county of Erie and State of New York, have invented a certain new and useful Improvement in Journal-Box-Pack-
5 ing Retainers, of which the following is a full, clear, concise, and exact description, reference being had to the accompanying drawings, forming a part of this specification.

This invention relates to improvements in journal box packing retainers.

It is the common practice in the operation 15 of railway cars, to pack the journals with oil-soaked waste in such a manner that the waste extends not only beneath the journal but also over the end of the journal to a level approximately slightly below the lower 20 edge of the opening closed by the lid. This practice oftentimes results in the packing or waste getting in between the lid and the journal box proper, thus preventing the proper closing of the lid and permitting 25 the entrance of dirt and other foreign matter while the train is in motion. Not only this, but the packing which extends over the end of the journal serves no useful purpose and represents an unnecessary expense, 30 the amount of packing thus serving no useful purpose approximating about two pounds, under actual operating conditions.

The object of my invention is to provide a simple, inexpensive, retainer for holding 35 the packing required beneath the journal, thus doing away with the necessity of any packing at the end of the journal and effecting a material saving in the cost of packing and operation of cars.

Another and more specific object of the invention is to provide a retainer for the purpose specified, which retainer will exert a yielding pressure against the packing, the retainer being attached to the lid of the 45 journal box and shiftable with the latter from operative position when the lid is closed, to an inoperative position, to thereby permit the inspector to have ready access to the packing for the purpose of either 50 replacing it or poking it as is commonly done.

The invention furthermore consists in the improvements in the parts and devices and the novel combination of the parts and de- 55 vices, as herein shown, described and claimed.

In the drawing forming a part of this specification, Figure 1 is a vertical, sectional view of a journal box and associated parts showing my improvement in connection therewith, the journal box, lid, bearing, dust guard, etc., being of well known construction. And Fig. 2 is a vertical, transverse 60 sectional view, taken substantially on the line 2—2 of Fig. 1.

In said drawing, 10 denotes a journal box of well known form having side walls 11—11, bottom wall 12 and upwardly curved lower front wall 13. The lid 14 is pivotally connected to the box 10 as by pivot pin 15 and the lid is adapted to be held in either closed or open position by a plate spring 16 which coöperates with a lug 17 in a well known manner. Within the box is provided the usual rocker 18, brass 19 and dust 70 guard 20 which surrounds the journal 21. The journal is packed with oil-soaked waste or packing material 22 on the under side thereof, as clearly illustrated in the drawing.

For the purpose of maintaining the packing beneath the journal and preventing the same from working out at the end, I have provided my improved packing retainer, designated generally by the reference A. 85 Said retainer A, as shown, is formed of spring wire and is of substantially U-shape, as viewed in Fig. 2. The retainer comprises a pair of spaced parallel vertically extending arms 23—23 and an intermediate 90 crimped portion 24. At their upper ends, the arms 23 are provided with an in-turned extension 25 each of which fits within a curled portion 26 formed on an outwardly extending flange 27 of a clip 28 riveted or otherwise rigidly secured to the inner side of the lid 14. The crimped portion 24 which is formed by bending the wire alternately upwardly and downwardly, as clearly illustrated in Fig. 2, to thereby provide a relatively wide bearing surface against the end of the packing 22, is offset inwardly at substantially right angles to the plane defined by the arms 23, as will appear from Fig. 1, said arms 23 being provided with a curved 100 portion 29 to effect this result. As will be noted from an inspection of Fig. 1, the curved portions 29 bear against the inner face of the curved wall 13 of the journal box when the parts are in normal or operative 105 position.

As will be clear from the drawing, the

crimped intermediate portion 24 of the retainer is disposed below the collar 30 on the end of the journal when the parts are in operative position. When the inspector desires 5 to examine the interior of the journal box, he swings the lid 14 to open position in the usual manner and during this operation, it is apparent that the retainer A will be raised due to the fact that the pivotal connection 10 between the portions 24 and 25 will swing in an arc about the pivot pin 15. Consequently, the crimped portion 24 of the retainer will be elevated to a position clear of the packing so that the inspector has ready 15 access to the packing.

In this connection, attention is also directed to the fact that the arms 23 are spaced sufficiently apart to prevent any interference with the insertion of any tool by the inspector. 20 When the lid is returned to closed position, it is apparent that the retainer A will be forced downwardly and the bent corner portions 29 will slide down the curved wall 13 and thereby force the crimped section 25 24 into engagement with the packing and under spring tension. Furthermore, it will be observed that the connection between the retainer A proper and the clips 28 is in a vertical plane directly below the pivot pin 15 so that, even though the retainer A is 30 under spring tension when in operative position, it does not exert any opening force on the pivoted lid 14. As will be understood, the arms 23 of the retainer are sprung into 35 connection with the clips 28 and the same may be replaced or removed with a minimum of effort.

With the arrangement hereinbefore described, it is obvious that a material saving 40 in the amount of waste required is effected; the packing which is employed is effectively held in its proper place; ready access is permitted to the waste whenever the lid is opened; and furthermore, the proper circulation 45 of air within the journal box is in no way interfered with.

Although I have herein shown and described what I now consider the preferred embodiment of my invention, the same is 50 merely illustrative, and I contemplate all changes and modifications that come within the scope of the claims appended hereto.

I claim:

1. The combination with a journal box 55 having an inner curved face at the lower outer end thereof and a lid pivotally connected at its top to the box, of a packing retainer adjustably attached to said lid at points substantially vertically below the pivotal connection 60 between the lid and box and movable to operative position to press the packing when the lid is closed and movable

to an inoperative position when the lid is opened to permit ready access to the packing beneath the journal, the lower portion of 65 said retainer engaging said curved face of the box when the lid is moved to closed position to thereby force the lower portion of the retainer against the packing.

2. The combination with a journal box 70 having a lid, of a packing retainer formed from flexible wire bent to proper form, said retainer, when in operative position, having engagement with the lower portion of the front wall of the journal box whereby the 75 retainer is held under tension in engagement with the packing.

3. As an article of manufacture, a packing retainer, said retainer comprising a wire having a pair of spaced arms and an intermediate crimped connecting portion. 80

4. As an article of manufacture, a packing retainer, said retainer comprising a wire having a pair of spaced arms and an intermediate crimped connecting portion, said 85 crimped portion being offset at substantially right angles to the plane defined by said arms.

5. The combination with a journal box having a lid pivotally connected thereto, of 90 a packing retainer attached to said lid and movable therewith from inoperative position when the lid is open to an operative position when the lid is closed, said retainer being pivotally connected to the lid substantially vertically below the pivotal connection 95 between the lid and the box to thereby prevent the retainer exerting an outward pressure on the lid.

6. The combination with a journal box 100 having a lid pivotally connected thereto, of a packing retainer adapted to press against the packing beneath a journal within the box, said retainer comprising a wire bent to proper shape, said retainer bearing against 105 the lower front wall of the box when in operative position.

7. The combination with a journal box having a lid pivotally connected thereto, of 110 a packing retainer pivotally connected to said lid and at a point beneath the pivotal connection between the lid and box, said retainer comprising a wire bent to general U-shape, the arms of the U being connected by an intermediate crimped portion inwardly offset from the plane defined by said arms, the retainer having engagement with the inner face of the lower front wall of the box when in operative position. 115

In witness that I claim the foregoing I 120 have hereunto subscribed my name this 13th day of June, 1917.

JOHN McMULLEN.
